UNITED STATES PATENT OFFICE.

GEORGE A. BIRCH, OF RENSSELAER, NEW YORK.

DESIGN FOR A CUTTING-POINT FOR ICE-PLOWS.

SPECIFICATION forming part of Design No. 32,016, dated December 19, 1899.

Application filed November 18, 1899. Serial No. 737,530. Term of patent 7 years.

To all whom it may concern:

Be it known that I, GEORGE A. BIRCH, a citizen of the United States, residing at Rensselaer, in the county of Rensselaer and State of New York, have invented and produced a new and original Design for a Cutting-Point for Ice-Plows, of which the following is a specification, reference being had to the accompanying drawings, forming part thereof.

- 10 Referring to the accompanying drawings, Figure 1 is a side view of the cutting-point. Fig. 2 is a top plan view. Fig. 3 is a bottom plan view; and Fig. 4, a sectional view on the line 4-4, Fig. 1.
- 15 The leading or material feature of my new design consists in an arrow-head-shaped cutting-point having parallel blades extending from what may be called the "base" of the arrow-head. Thus, as shown, the body portion A of the point has a general triangular or arrow-head shape, the top and bottom a a' tapering toward each other and joining at the edge b. Extending from the base portion of the body are the parallel blades C C', leaving a space c between them. The top a is of practically rectangular shape, as best shown in Fig. 2, while the bottom a' tapers slightly from the edge b toward the blades C C'.

Having thus described my invention, what I claim as new, and desire to secure by Letters Patent, is—

The design for a cutting-point for ice-plows, substantially as herein shown and described.

In testimony whereof I have signed my name to this specification in the presence of 35 two subscribing witnesses.

GEORGE A. BIRCH.
